UNITED STATES PATENT OFFICE.

GEORGE W. WESTER, OF HARRIMAN, TENNESSEE, ASSIGNOR TO JOHN A. MANLEY,
TRUSTEE, OF HARRIMAN, TENNESSEE.

ART OF MAKING DIGGING-TOOLS.

1,187,876.

Specification of Letters Patent. Patented June 20, 1916.

Application filed October 29, 1914. Serial No. 869,255.

To all whom it may concern:

Be it known that I, GEORGE W. WESTER, a citizen of the United States, residing at Harriman, in the county of Roane and State 5 of Tennessee, have invented a new and useful Improvement in the Art of Making Digging-Tools, of which the following is a specification, reference being had to the accompanying drawing.

10 My improvement relates particularly to art of making digging tools to which the name, "hoe", is ordinarily applied. The finished tool is a compound tool comprising two parts, one being a hoe blade similar to the 15 blade of an ordinary hoe and the other part being a group of tines set parallel to each other and at the same angle to the handle as a hoe blade is ordinarily set. This part of the tool is known to the trade as a "potato 20 hoe".

The object of the improvement is to provide an economical method and blanks for the production of such tool.

In the accompanying drawings, Figure 1 25 is an elevation of the tool looking toward and in the direction parallel to the handle of the tool; Fig. 2 is a section on the line, 2—2, of Fig. 1; Fig. 3 is a plan of a continuous metal blank bar or plate out of 30 which blank sections are cut for making the tool; Fig. 4 is a section on the line, 4—4, of Fig. 3; Fig. 5 is a modification of the form shown in Fig. 4; Fig. 6 is a plan of a blank section cut from the plate shown in Fig. 3; Fig. 7 is a view showing another form or 35 mode of cutting blank sections out of the blank plate or bar; Fig. 8 is a view of a blank section cut from the blank shown by Fig. 7; Fig. 9 is a front view of a completely cut blank section formed from the bar section shown by Fig. 6; Fig. 10 is a 40 view of the same blank, looking toward the right, as shown in Fig. 9; Fig. 11 is a front view of a completely cut blank of a modified form; Fig. 12 is a view of the same 45 blank, looking toward the right, as shown in Fig. 11.

Referring to Figs. 1 and 2, the tool comprises a shank, C, four hoe tines, A, A, and 50 a hoe blade, B, these parts being integral and preferably formed out of a single piece of metal as hereinafter described. The shank, C, is adapted to enter a socket in the end of the handle, D. The hoe blade stands 55 at one side of the axial line of the shank, C,

and is preferably inclined somewhat toward the handle, D. The group of tines stands at the opposite side of the shank axis. Said tines are parallel to each other and somewhat inclined toward the handle, D, as 60 shown in the drawings. This makes a double or compound tool, as above stated, one part being a potato hoe and the other being an ordinary hoe blade. The blade, B, may be turned toward the ground and used for 65 cutting and digging; or the group of tines may be turned toward the ground and used for digging and tearing the earth and plants. The two portions of the tool may be used alternately, as best suited for the work to be 70 done, the blade, B, being best suited for cutting, while the tines are best suited for penetrating and tearing. The manufacture of this compound tool will next be described.

Referring to Figs. 3 and 4, these figures 75 show a blank plate or bar, E, which is continuous or of indefinite length, and from which blank sections are to be cut, each of which sections contain metal out of which the compound tool is to be formed with a 80 minimum of labor and a minimum waste of metal. The blank bar or plate, E, is cut transversely on the lines, F, F, to form a section blank. Said bar is to be rolled of suitable width and thickness to adapt each 85 blank section to provide in convenient form the amount of metal necessary to make the tool. The entire blank plate or bar is in this manner cut into blank sections.

Referring now to Fig. 6, slits, G, G, are 90 cut from the margin of the blank section to nearly the middle longitudinal line of said section; and slits, H, H, are cut from the adjacent end of said section to each inner end of the slits, G, G. This separates the 95 approximately rectangular fragments, I, I, from the blank section and leaves a stub, J, on the middle longitudinal line of the section. This stub contains a suitable amount of metal to form a shank, C; and said stub 100 is forged to form such shank, this being preferably done without bending said stub.

From the opposite end of the blank section, slits, L, L, are cut parallel to the length of the blank section and nearly to the line 105 of the slits, G. The two outer ends of the slits, L, are connected by short transverse slits, M, whereby fragments, N, N, are detached from the blank section. The two middle slits, L, are not thus connected. At 110

each side of each space from which a fragment, N, is taken, a straight bar, O, is left. Between the two middle bars, O, a relatively wider bar or tongue, P, is left. Between the 5 bars, O and P, on one hand, and the stub, J, on the other hand, a transverse head, K, is left. The bars, O, are bent to one side of the blank section plane, such bending being chiefly close to the head, K, and being far enough to put the bars a little beyond or across a plane which is perpendicular to the blank section plane and cuts the latter adjacent the base of the bars, O, so that the angle 10 between said bars and the shank, C, is a little less than a right angle. Each of said bars, O, is forged and finished to form a tine, A, in the finished tool. The thickness of the blank bar or plate is preferably as nearly as may be the thickness of the finished tines, 15 and the slits, L, L, are preferably placed so as to form the bars, O, as nearly as may be of the width of the finished tool, in order that the bars, O, may require a minimum amount of labor and treatment to form the 20 finished tines.

The bar or tongue, P, is bent out of the plane of the blank section at the side of the latter opposite the tines, A, A, the bending being chiefly close to the head, K, and said 25 bar, P, is preferably bent far enough to make the angle between it and the shank, C, a little less than a right angle. And said bar or tongue, P, is forged and otherwise treated to form a hoe blade, B, which is 30 wide relative to the width of the tongue, P. Said hoe blade is preferably formed like the blades of ordinary hoes used for cultivating gardens, etc., and said hoe blade may be of such size relative to the group of tines, A, A, 35 40 as the work to be done by the tool seems to demand. When the tool is finished, the stem of the hoe blade stands opposite the space between the middle tine bars.

The portion, Q, of the blank plate or bar, 45 E, which will lie between the middle slits, L, L, of the blank sections and forms the tongue, P, may be and preferably is of such thickness as to put into the bar or tongue, P, the amount of metal, and no more, needed 50 to form the finished hoe blade. In Fig. 4, the portion, Q, is made thicker at one side of the plate or bar than the thickness of the body of said plate or bar. In Fig. 5, said portion, Q, is thickened at both sides of the 55 plate or bar. It will be observed that thus providing in said bar or tongue, P, the precise amount of metal required for forming the hoe blade economizes both labor and material.

60 In Fig. 7, the transverse cuts, E; E, are

not continuous. Each such cut extends from the edge of the bar to the portion, Q, and is then offset along and across the part, Q, so as to put a stub, J, on one end of the blank section. But this correspondingly shortens 65 the bar or tongue, P, and for that reason this portion of the blank bar must be thickened sufficiently to compensate for this shortening of said bar or tongue. Making the cuts, E, E, in the manner last above described avoids 70 making the waste fragments, I, I, shown in Fig. 6.

I claim as my invention,

1. In the art described, a metal blank section cut from a flat bar to comprise a transverse head, a stub on one side of said head, 75 a tongue on the opposite side of said head and at the middle of said section, and tine bars on said head at opposite sides of said tongue, substantially as described.

2. In the art described, a metal blank section cut from a flat bar to comprise a transverse head, a stub on one side of said head, a tongue on the opposite side of said head and at the middle of said section, and tine 80 bars on said head at opposite sides of said tongue, said tongue containing more metal than any of said tine bars, substantially as described.

3. In the art described, a metal blank section cut from a flat bar to comprise a transverse head, a stub on one side of said head, a tongue on the opposite side of said head and at the middle of said section, and tine 85 bars on said head at opposite sides of said tongue, said tongue and said stub being thicker than the tine bars, substantially as described.

4. The herein described method of forming the compound tool herein described, 100 which method consists in forming a metal blank section of approximately the width of the finished tool and having at one end a stub, shaping the stub to form a shank, slitting said section parallel to its side edges to 105 form a middle tongue and tine bars, bending the tine bars to one side of the plane of the blank section and finishing them as tines and bending the tongue to the other side of said plane and expanding and finishing it as a 110 hoe blade, substantially as described.

In testimony whereof I have signed my name, in presence of two witnesses, this 27th day of October, in the year one thousand nine hundred and fourteen.

GEORGE W. WESTER.
